(57) **CLAIM**

The ornamental design for a clip for attachment to a clipboard holding paper and other objects, as shown and described.

DESCRIPTION

FIG. 1 is a perspective view showing the top left and front of the clip for attachment to a clipboard holding paper and other objects;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a second perspective view thereof, the partial showing of a clipboard depicted by means of broken lines is for illustrative purposes only and forms no part of the claimed design.
